UNITED STATES PATENT OFFICE.

HANNAH LANG, OF NEW YORK, N. Y.

DESIGN FOR A COVER FOR HOT-WATER BAGS.

SPECIFICATION forming part of Design No. 31,623, dated October 10, 1899.

Application filed September 16, 1899. Serial No. 730,775. Term of patent 7 years.

To all whom it may concern:

Be it known that I, HANNAH LANG, a citizen of the United States, residing at New York, (Brooklyn,) in the county of Kings and State 5 of New York, have invented and produced a new and original Design for Covers for Hot-Water Bags; and I do hereby declare the following to be a full, clear, and exact description of the invention, such as will enable 10 others skilled in the art to which it appertains to make and use the same.

The drawing shows a face view of my cover for hot-water bags.

As shown in the drawing, the bag is provided with a straight lower edge A and arc-shaped inwardly-curved sides B, the corners b being rounded, as shown, said curved sides terminating at a point b' near the upper edge of the bag, and thence flaring outwardly, as 20 at B'. The upper edge of the bag is scalloped, as shown at C. The surface of the bag from the lower edge A to the points b' is ridged horizontally, as shown at D, the portion intermediate the ridges having a web-like appearance, as shown at D'.

Extending upwardly at regular intervals from the upper ridge D are strips E, connecting the ridged portion of the bag with the scalloped portion thereof. This portion is provided with the scalloped upper edge c, a straight lower edge c', and a ridge c², intermediate its length and parallel with said straight edge. That part of the scalloped portion intermediate the edges and the ridge c² has a web-like appearance, as shown at c'. 35

Intermediate and below the outer surface of strips E are secured cords F, projecting to either side of the bag and terminating in tassels F', as shown.

Having thus fully described my design, 40 what I claim, and desire to secure by Letters Patent, is—

The design for a cover for a hot-water bag, substantially as herein shown and described.

Signed at Brooklyn, New York, August 9, 45 1899, in the presence of two witnesses.

HANNAH LANG.
